BULKHEAD DOOR STRUCTURE

Young K. Buell, New York, N. Y., assignor to
 Raymond M. Hilliard as Commissioner of Wel-
 fare of the city of New York

Substituted for abandoned application Serial No.
 464,024, October 31, 1942. This application
 May 5, 1948, Serial No. 25,289

4 Claims. (Cl. 114—117)

1

This invention relates to new and useful im-
 provements in a floating island. This application
 is a substitute for my abandoned application
 Serial No. 464,024 filed October 31, 1942.

More specifically, the invention proposes the
 construction of a floating island in the nature of
 a ship having many decks in its hull, each of
 which is sub-divided into a plurality of comparti-
 ments by means of partitions with openings lead-
 ing from one compartment to the other in a man-
 ner to permit persons to move about between
 compartments.

Another object of this invention proposes pro-
 viding the openings between compartments with
 tubular extensions upon which caps are adapted
 to be threadedly engaged in a manner to water-
 tightly seal the compartments from one another
 and to frustrate the spread of fire when a fire
 breaks out in one of the compartments due to
 leaks in gasoline tanks, or when a torpedo hits
 the ship, and thus to keep the ship afloat.

Still another object of this invention is to pro-
 vide a device particularly adaptable to our pres-
 ent wartime production when it is the aim of
 shipbuilders to produce ships which are not so
 easy to sink. Furthermore, ships are being built
 with great speed, large ships taking only ten days,
 and it is proposed to provide a means for lessening
 sinkings at sea without increasing the pro-
 duction schedules of the nation's shipbuilders.

Another object of this invention proposes the
 construction of a device adapted to all kinds of
 ships, such as: battleships, destroyers, aircraft
 carriers, troopships and the like, and designed in
 a manner to make them substantially unsinkable
 and therefore safer to transport large quantities
 of men, ammunition and other war supplies and
 equipment.

Still another object of this invention is the
 construction of a compartment sealing device ar-
 ranged in a manner to make the world's seacraft
 safe against the ravages of submarines making
 it feasible for a nation well supplied with these
 ships to wage war at great distances from their
 home bases.

A still further object of this invention proposes
 a novel means for rotatively supporting the cap
 while at the same time being pivotally supported
 at the side of the opening it is to close in a
 manner to permit the cap to move axially of the
 opening while being screwed on and removed from
 position relative to the opening.

Still further it is proposed to provide the cap
 with a projection adapted to be engaged by an

2

appropriate turning tool for engaging the cap in
 position upon its tubular extension.

Still another object proposes the provision of a
 means for connecting a plurality of caps together
 for unitary movement in a manner to permit a
 gang of these caps to be simultaneously opened
 and closed when desired.

It is a further object of this invention to con-
 struct a floating island which is simple and dur-
 able and which is adapted to mass production
 methods and reasonable to build.

For further comprehension of the invention,
 and of the objects and advantages thereof, refer-
 ence will be had to the following description and
 accompanying drawings, and to the appended
 claims in which the various novel features of the
 invention are more particularly set forth.

In the accompanying drawings forming a ma-
 terial part of this disclosure:

20 Fig. 1 is a side elevational view of a floating
 island in the nature of an aircraft carrier con-
 structed in accordance with this invention.

Fig. 2 is a vertical sectional view taken on the
 line 2—2 of Fig. 1.

25 Fig. 3 is a side elevational view of a floating
 island in the nature of a troopship constructed
 in accordance with this invention.

Fig. 4 is a horizontal sectional view taken on the
 line 4—4 of Fig. 3.

30 Fig. 5 is a front elevational view of one of the
 compartment sealing means per se.

Fig. 6 is a plan view of Fig. 5.

Fig. 7 is a horizontal enlarged sectional view
 taken substantially on the line 7—7 of Fig. 5.

35 Fig. 8 is a side elevational view of a floating
 island in the nature of a warship constructed in
 accordance with this invention.

Fig. 9 is a horizontal sectional view taken on the
 line 9—9 of Fig. 8.

40 Fig. 10 is a front elevational view of one of the
 compartment sealing means looking in the di-
 rection of the line 10—10 of Fig. 9.

Fig. 11 is a partial horizontal sectional view on
 the line 11—11 of Fig. 10.

45 Fig. 12 is a schematic wiring diagram of the
 device.

The floating island, according to the first form
 of this invention, is in the form of an aircraft
 carrier 10 (Fig. 1) or a troopship 11 (Fig. 3).
 The interior of the hull 12 of each of these ships
 is divided into a plurality of super-imposed deck
 areas 13 with each deck area being sub-divided
 into a plurality of separate compartments 14 by
 means of partitions 15, see Figs. 2 and 4, with the
 exception of one or more of the upper decks which

may be left open for aircraft, tanks and the like.

Each of the compartments are connected with adjoining compartments by means of openings 16 formed in the partition walls 15. These openings 16 are circular and are surrounded on one side of the partition wall 15 by an externally threaded tube 17. The tube 17 has an externally extended flange 18 inwards of its outer end and attached to the material of the partition 15 surrounding the opening 16 for supporting the tube 17 in position surrounding the opening 16.

A bracket 19 is mounted on the partition 15 to one side of the tube 17. This bracket 19 consists of a plate 20 attached to the face of the partition 15 and from which spaced lugs 21 extend. A rod 22 is extended between the lugs 21 and has the superimposed ends of a plurality of links 23 rotatively engaged thereon. These links 23 are held spaced from each other by means of spacer elements 24.

A yoke 25 has its arms 26 pivotally attached to the outer periphery of a ring 27 by means of pins 28. The opposite side of the yoke 25 is formed with spaced lugs 29 directed towards the free ends of the links 23. A rod 30 extends between the lugs 29 and passes rotatively through the free ends of the links 23. Spacer elements 31 are mounted on the rod 30 between the ends of the links 23 for maintaining these free ends spaced.

A cap 32 is formed with a groove 33 rotatively engaged by the ring 27 for rotatively supporting the cap 32 on the ring 27. The cap is threaded internally and is adapted to be threaded upon the tube 17 as shown in Fig. 7. Packing washers 34 are disposed between the inner ends of the cap 32 and the adjacent face of the flange 18 of the tube 17 for water-tightly sealing these contacting surfaces.

The outer face of the cap 32 is formed with an extension 35 adapted to be engaged by a turning tool (not shown on the drawings) for facilitating the turning of the cap 32 relative to the tube 17. The starting alignment of the thread is indicated by the arrows 32^a on the cap 32 and 32^b on the ring 27. One side of the ring 27 has a set screw 36 threadedly engaged therethrough and is formed with a circular cutting edge 36^a bearing against one side of the cap 32 for securely locking the cap 32 against turning relative to the ring 27 when desired to make the device immovable against any pressure or vibration.

The operation of the device is as follows:

Normally the caps 32 are in their open positions providing a free passage between compartments through the tubes 17 which are of a diameter to permit a man to walk through upright. When the ship is about to be torpedoed or if a fire breaks out on the ship the caps 32 are closed isolating each compartment 14 preventing water from entering through a hole in one compartment from flooding all compartments or fire from spreading from one compartment to the other.

In the form of the invention illustrated in Figs. 8 to 12, the floating island is in the nature of a warship 40 which might be a battleship, cruiser, destroyer or the like. The hull 42 of this warship 40 is divided into a plurality of compartments 14 having openings 16 adapted to be closed by caps 32'. The caps 32' in this form of the invention, however, are adapted to be closed in gangs permitting a number of caps to be closed simultaneously by one man.

The pins 28 which support the ring 27 having their shanks passed through elongated slots

41 formed in the ends of the arms 26 of the yoke 25. Springs 42 operate between the ends of the slots 41 and opposite sides of the shanks of the pins 28 for holding the shanks normally centrally of the slots 41.

Those caps 32' which are arranged in a straight line have their yokes connected together by a rod 43 extended between the top ends of the pins 28 which pass through the top arms 26 of the yoke 25. Those top pins 28 have longer shanks extended through the rod 43, spacer members 23^a between the adjacent faces of the rod 43 and the top arms 26 of the yoke 25, through the slots 41 in the top arms of the yokes 25 and into the rings 27. Intermediate of its ends the rod 43 is formed with a grip 44 adapted to be manually gripped to move the rod 43 and simultaneously align all the caps 32' with the free ends of their respective tubes 17.

Teeth 45 are formed on the periphery of the cap 32'. Supported between the arms 26 of the yoke 25 is a motor and gear reduction unit 46 having its final pinion 47 meshing with the teeth 45. An electrical circuit 50 is provided for connecting the motors together for unitary movement and provides the means for screwing and unscrewing all the caps as a unit.

The electrical circuit 50 includes a source of power and a reversing switch 48. This reversing switch 48 is adapted to be mounted on a wall adjacent the grip 44 of the rods 43 to be in position to be manipulated by the person operating the rod. Throwing the switch 48 in one direction will cause all the motors to turn in one direction to screw the caps 32 onto the tubes and throwing the switch 48 in the opposite direction will cause the motors to turn in the opposite direction and unscrew the caps 32' from the tubes 17.

The springs 42 permit the caps to be independently screwed onto and removed from the tubes 17 manually merely by compressing the springs as the rings move relative to the yokes 25 and rod 43. That is so, because the springs 42 permit movement of the rod 43 relative to the other caps of a connected group whenever one of the caps is being independently manually screwed into its closed position.

In other respects this form of the invention is similar to the previous form and like reference numerals identify like parts in each of the several views.

Instead of an electric motor, a spring motor, compressed air motor or any other turning device may be used for rotating the gear 47.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In a device of the class described, a wall formed with a plurality of openings, links pivotally mounted on said wall adjacent to said openings, a yoke for each of said openings and said yokes being pivotally mounted on said links for swinging towards said openings, a ring located between the arms of each yoke and having diametrically opposite radially projecting pins passing through slots in said arms and said slots extending at right angles to said wall with said arm substantially parallel to said wall, resilient

means in said slots for resiliently holding said pins centrally in said slots, a connecting rod connecting together one of the pins of each ring, a cap rotatively mounted within each ring for threadedly engaging said openings in said wall and provided on its periphery with gear teeth, a drive pinion for each cap meshing with said gear teeth and having its axis parallel with the axis of the cap, and means for driving said pinions in one direction or the other, whereby when the threads of one or more of said caps threadedly catches the threads of one or more of said openings a force will be transmitted by said connecting rod which will assist the other caps in catching the threads of their openings.

2. In a device of the class described, a wall formed with a plurality of openings, links pivotally mounted on said wall adjacent to said openings, a yoke for each of said openings and said yokes being pivotally mounted on said links for swinging towards said openings, a ring located between the arms of each yoke and having diametrically opposite radially projecting pins passing through slots in said arms and said slots extending at right angles to said wall with said arms substantially parallel to said wall, resilient means in said slots for resiliently holding said pins centrally in said slots, a connecting rod connecting together one of the pins of each ring, a cap rotatively mounted within each ring for threadedly engaging said openings in said wall and provided on its periphery with gear teeth, a drive pinion for each cap meshing with said gear teeth and having its axis parallel with the axis of the cap, and means for driving said pinions in one direction or the other, whereby when the threads of one or more of said caps threadedly catches the threads of one or more of said openings a force will be transmitted by said connecting rod which will assist the other caps in catching the threads of their openings, said resilient means comprising springs in the end portions of said slots engaging opposite sides of said pins.

3. In a device of the class described, a wall formed with an opening, links pivotally mounted on said wall adjacent said opening, a yoke pivotally mounted on said links for swinging to-

ward said opening, a ring located between the arms of said yoke, a cap rotatively mounted within said ring for threadedly engaging said opening closing the same, means on said yoke and engaged with said cap for rotating said cap in one direction or the other, and means supporting said ring between the arms of said yoke so that said ring and cap are free for slight movement in a direction at right angles to said yoke.

- 10 4. In a device of the class described, a wall formed with an opening, links pivotally mounted on said wall adjacent said opening, a yoke pivotally mounted on said links for swinging toward said opening, a ring located between the arms of said yoke, a cap rotatively mounted within said ring for threadedly engaging said opening closing the same, means for rotating said cap in one direction or the other, and means supporting said ring between the arms of said yoke so that said ring and cap are free for slight movement in a direction at right angles to said yoke, said supporting means comprising pins extending from diametrically opposite sides of said ring, elongated slots formed in the arms of said yoke with their lengths extended at right angles to said arms and into which said pins are slidably engaged, and springs in the end portions of said slots and engaging opposite sides of said pins.

YOUNG K. BUELL.
